(57) **CLAIM**

The ornamental design for a control panel for a magnetic-field based medical device, as shown and described.

DESCRIPTION

FIG. 1 is a front-left side perspective view of a control panel for a magnetic-field based medical device showing our new design thereof on an unclaimed magnetic-field based medical device;

FIG. 2 is a front-left side perspective view of the control panel for a magnetic-field based medical device showing our new design thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The dash-dash broken lines shown in FIGS. 1–8 represent elements of the control panel for a magnetic-field based medical device that are excluded from the claim and form no part thereof.
